CLAIM

The ornamental design for a multi-channel conduit connector for treating deep vein thrombosis, as shown and described.

DESCRIPTION

FIG. 1 is a perspective view of the multi-channel conduit connector for treating deep vein thrombosis which illustrates the new design;

FIG. 2 is a top plan view thereof;

FIG. 3 is a right side view thereof;

FIG. 4 is a bottom view thereof;

FIG. 5 is a left side view thererof;

FIG. 6 is a back view thereof;

FIG. 7 is a front view thereof;

FIG. 8 is a perspective view of second embodiment of the multi-channel conduit connector for treating deep vein thrombosis which illustrates the new design;

FIG. 9 is a top view of FIG. 8;

FIG. 10 is a right side view of FIG. 8;

FIG. 11 is a bottom view of FIG. 8;

FIG. 12 is a left side view of FIG. 8;

FIG. 13 is a back view of FIG. 8; and,

FIG. 14 is a front view of FIG. 8.
